UNITED STATES PATENT OFFICE.

JOHN F. PATTERSON, OF WARREN, OHIO.

DISHWASHER.

Application filed July 14, 1919. Serial No. 310,599.

The present invention relates to dishwashing machines and the principal object thereof is to provide a dishwashing machine which will effectively clean the dishes and 5 at the same time preventing injuring or breaking of the same.

Another important object of the invention is to provide a dishwashing machine wherein sprays are played upon the dishes in such a 10 manner as to subject the entire surface of the dishes to the sprays.

A further object of the invention is to provide a dishwashing machine wherein separate compartments are provided, one for 15 the cups and easily broken dishes, the other compartment having a novel rack therein for spraying plates to hold the same in position while being sprayed.

A still further object of the invention is 20 to provide a dish washing machine having a novel spray associated therewith which may be adjusted to spray any desired portion of the tray containing the dishes.

An additional object of the invention is 25 to provide a dishwashing machine which is simple in construction, consists of few parts that may be easily assembled and disassembled, and which may be manufactured and placed on the market at a comparatively 30 small cost.

With the above and other objects and advantages in mind which will appear as the description proceeds, the invention resides in the combinations and arrangements of 35 parts, details of constructions, operations and formations, and general assemblage all of which will be further enlarged upon and described hereafter, the invention being illustrated in the accompanying drawing, 40 wherein:—

Figure 1 is a longitudinal sectional view of one of the sprays;

Figure 2 is a side elevation of the same;

Figure 3 is an end elevation of the spray;

45 Figure 4 is a view partly in longitudinal cross section and partly in elevation of the valve and soap container used in conjunction with the invention parts being broken away;

50 Figure 5 is a top plan view of the same;

Figure 6 is a side elevation of the valve and soap container, parts being broken away;

55 Figure 7 is a plan view of the assembled dish washer;

Figure 8 is a longitudinal section through

the device, certain parts being shown in elevation;

Figure 9 is a vertical transversely sectional view of the dishwasher taken on line 60 9—9 of Figure 7;

Figure 10 is an end elevation of the same;

Figure 11 is a plan view of the draining rack;

Figure 12 is a transversely sectional view 65 taken on line 12—12 of Figure 11.

Like characters of reference designate like parts on all of the views.

There is provided a receptacle which consists of sections 5 and 6, the section 6 being 70 connected with the section 5 at the upper edge thereof. A wire 7 encircles the sections at their meeting edges.

An improved spray is provided which consists of a relatively short pipe 8 having an 75 outlet opening 9 at one side thereof. Extending transversely through the pipe 8 is a threaded valve 10 having one end tapered and formed into an annular head, the tapered part being disposed in the opening 9 and the head 10 projecting from the same. A series of these sprays are employed which are connected together through the medium of pipes 11, the sprays being disposed upon 80 the walls of the receptacle and extending entirely around the same, a common water inlet valve being provided for the sprays.

There is provided a truncated valve casting 13 provided with nipples 14 at diametrically opposite points, one of which constitutes an inlet port and the other an outlet port. A removable cap 15 is threaded on the lower end of the casing by means of which access may be had into the interior of the same. Extending vertically from the 95 casing is a duct 16 which communicates with the outlet port. A hollow valve stem 17 extends vertically from a rotatable valve 18 through the casing 13 and is provided with a lateral port 19 adapted to register 100 with the duct 16. A tube 20 is disposed within the hollow valve stem 17 and is spaced therefrom and extends within the valve 18 and connected therewith. This tube 20 is longer than the stem 17 and extends out of the upper end of the same and 105 extends within a soap container or receptacle 21 supported upon the upper end of the stem 17. A handle 22 is fixed to the upper end of the valve stem whereby the 110 valve is rotated. Extending from the valve 18 is a nipple 23, the bore of which is

disposed in alignment with the tube 20 and encircling the nipple is an expansible coil spring 25 which bears against the valve and cap 15 to retain this valve against the casing 18. A baffle plate 26 extends, transversely across the casing and its lower edge is slightly raised from the cap 15 to permit the water to pass thereunder and also into inlet 12, to the sprays. This plate depends 10 from the valve and rotates therewith and is adapted to be disposed at right-angles to the position shown in Figure 5 to allow the water to flow through the valve casing. When the valve stem is rotated so the port 19 registers with the port 16 the water passing through the valve casing flows through the tube 20 into the receptacle thereon down into the valve stem and out by way of ports 19 and 16 into port 12 and finally to the sprays to be played upon the dishes. Then if it is desired to spray clear water upon the dishes the valve is rotated to arrange the plate at right angles to the position shown in 15 Figure 1.

25 Removably mounted in the lower portion of the receptacle 5 is a tray 27 which has its bottom perforated as shown at 27'. Ears 28 are struck inwardly from the upper and lower portions of the end walls of this tray 30 and are engaged by the downturned ends of bars 29 resting on the ears. These bars are designed to hold dinner plates and the like in upstanding positions as shown by broken lines in Figure 9.

35 A basket 30 is supported above bars 29 and is adapted to contain fragile dishes such as pitchers, cups and the like. This basket is adapted to be supported by brackets 33 engaged by bent rods 34 extending from the bottom of the basket as shown in Figure 8.

40 In Figures 11 and 12 I have shown a drain rack which consists of a receptacle 31 in which is mounted a foraminated false bottom 32 for supporting the dishes after they have been washed and a removable tray supported at the top of the receptacle.

45 In using the apparatus herein described the larger plates are placed on end within the tray 27 where they are supported in upstanding positions by the rods 29. Smaller articles to be washed are placed in the basket 30 and this basket is lowered to position where it will be supported by the brackets 33 engaging the fingers 34. When the basket 30 is thus disposed above the tray 27 extends into the space surrounded by the pipe 8. After the receptacle has been closed

the valve mechanism is actuated as heretofore explained so that water will be directed 60 upwardly, inwardly and downwardly from the openings 9 and the water issuing from one opening will enter both the tray and the basket and, by violent impact against the contents thereof, quickly clean the same. 65 Obviously one set of outlets can thus be used for both of the superposed containers and fresh water will be directed from the outlets to both containers. The pipe is supported parallel with the bottoms of the 70 basket and tray and between the upper basket and the walls of the container or main receptacle. Thus the pipes are out of the way and the delivery of water will not be interfered with by the dishes or other 75 articles piled up in the apparatus.

This disclosure is illustrative only and it will be understood that the same may be modified and altered in many respects and that such limits of modification are only 80 governed by what is claimed.

What is claimed is:

In a dish washing machine the combination with a receptacle, of superposed spaced containers within the receptacle, the upper container being foraminous and spaced from the walls of the receptacle, a pipe extending continuously around but spaced from the upper container and located between said container and the wall of the receptacle, 85 said pipe being parallel with the bottoms of the containers, there being a series of apertures in the pipe opening inwardly therefrom toward the bottom portion of the upper container, and a series of apertures opening 90 upwardly from said pipe to deliver jets between the upper container and the walls of the receptacle, an outwardly tapered valve 95 for controlling the flow of water through each aperture and a spreading head at the 100 outer end of the valve supported thereby outwardly beyond the opening, the spreading head adjacent one series of openings constituting means for breaking up the jets of water issuing from said openings and spraying them inwardly and upwardly and the heads upon the valves adjacent the other openings constituting means for breaking up the jets issuing from said openings to spray them inwardly, upwardly and downwardly 110 into both containers.

In testimony that I claim the foregoing as my own, I have hereto affixed my signature.

JOHN F. PATTERSON.
